LAWN SPRINKLER

Henry J. Talge, Kansas City, Mo., assignor, by mesne assignments, to Rival Manufacturing Company, a corporation of Missouri

Filed June 20, 1963, Ser. No. 75,448

Term of patent 14 years

(Cl. D91—1)

FIG. 1 is a top plan view of a lawn sprinkler embodying my new design;

FIG. 2 is a side elevational view of same;

FIG. 3 is an end elevational view of same taken from the left-hand end of FIG. 2;

FIG. 4 is an end elevational view of same taken from the right-hand end of FIG. 2;

FIG. 5 is an end elevational view taken along line 5—5 of FIG. 2 in the direction of the arrows; and

FIG. 6 is an enlarged fragmentary perspective view taken from the side shown in FIG. 3.

The dominant features of the design reside in the portions shown in solid lines.

I claim:

The ornamental design for a lawn sprinkler, as shown and described.
